[57] CLAIM

The ornamental design for a wrist-attachable pacifier, as shown and described.

DESCRIPTION

FIG. 1 is a perspective view of a wrist-attachable pacifier showing my new design;

FIG. 2 is a side elevational view thereof, the side opposite being a mirror image of the side shown in FIG. 2;

FIG. 3 is an end elevational view thereof;

FIG. 4 is an end elevational view thereof, opposite that shown in FIG. 3;

FIG. 5 is a top plan view thereof; and,

FIG. 6 is a bottom view thereof.

FIG. 2.

FIG. 3.

FIG. 4.

FIG. 5.

FIG. 6.
